Primary Examiner — Robin V Webster*(74) Attorney, Agent, or Firm* — Smith Risley Tempel Santos LLC; Gregory Scott Smith(57) **CLAIM**

The ornamental design for a cleaning cloth, as shown and described.

DESCRIPTION

FIG. 1 is a top plan view of the cleaning cloth; FIG. 2 is a bottom plan view of the cleaning cloth illustrated in FIG. 1;

FIG. 3 is a perspective view of the cleaning cloth illustrated in FIG. 1 with a cross-section proximate to line 3 as illustrated in FIG. 1;

FIG. 4 is a first side elevation view of the cleaning cloth illustrated in FIG. 1;

FIG. 5 is a second side elevation view of the cleaning cloth illustrated in FIG. 1;

FIG. 6 is a first end elevation view of the cleaning cloth illustrated in FIG. 1; and,

FIG. 7 is a second end elevation view of the cleaning cloth illustrated in FIG. 1.

The cleaning cloth includes two external sheets with material sandwiched there between. The texture in the drawing is provided to aid in the understanding of the cleaning cloth and forms no part of the invention. The broken lines illustrated in the figures form no part of the claim.
